UNITED STATES PATENT OFFICE

2,031,491

SOLE ATTACHING APPARATUS

John T. Lancaster, Newton, Mass., assignor to
 United Shoe Machinery Corporation, Paterson,
 N. J., a corporation of New Jersey

Application December 28, 1934, Serial No. 759,545

16 Claims. (Cl. 12—33)

This invention relates to apparatus for attaching soles to shoes, and particularly to improved means for holding down the welt or sole extension of a welt or other shoe having an extension edge sole, to prevent the extension from rolling up against the side of the shoe when heavy pressure is applied to the sole, as in the process of attaching it to a shoe by the cement method.

In the machines commonly employed for the cement attachment of soles to shoes there is a pressure pad arranged upon a support which usually is in the form of a pad box, combined with an overhead yoke or other means for sustaining a toe support and a heel supporting abutment for holding the lasted shoe against the pressure applied to the sole by the pad. In some machines the yoke is integral with the pad box and in others it is separate and movable relatively to the pad box.

It is an object of the present invention to provide an improved welt holddown which is applicable to sole attaching machines of various types, regardless of whether the toe and heel supporting abutments are in fixed relation to the pad box or not.

In the accomplishment of this object, a feature of the invention consists in the provision of a welt holddown sustained by the pad support or box independently of the pad box yoke and of the heel and toe supports. In the embodiments of the invention illustrated herein, the welt holddown is sustained in operative position over the pad by a bracket fixed to the side of the pad box.

Another feature of the invention, particularly useful when an inflatable pad is employed, consists in the provision of means for raising and lowering the holddown to permit it to be accommodated easily to the height of the welt crease of a shoe upon the pad, regardless of the position of the sole engaging surface of the pad.

Other features of improvement are to be recognized in various swinging and sliding movements of which the holddown apparatus is capable in order to facilitate accurate positioning of the holddown with respect to the shoe and connections whereby a plurality of these movements may be effected by manipulation of a single handle.

Further novel features of improvement contributing to ease and accuracy in operation and uniformity in results will be perceived and readily understood from reading the following detailed description of two illustrative embodiments of the invention in connection with the accompanying drawings, in which

Fig. 1 is a side elevation of a press unit equipped with the welt holddown apparatus;

Fig. 2 is a plan view of the same;

Fig. 3 is an end elevation;

Fig. 4 is a sectional view, upon the line IV—IV 5 of Fig. 2, of a detail of the welt holddown operating mechanism;

Fig. 5 is a side elevation showing a modified form of the apparatus;

Fig. 6 is a plan view of the same;

Fig. 7 is an end elevation of the same; and

Fig. 8 is a sectional detail, taken upon the line VIII—VIII of Fig. 5.

In the drawings 10 indicates the pad box of a press unit for cement attaching extension edge 15 soles to shoes and 12 indicates an inflatable pad, the admission of fluid under pressure to which is controlled by a valve 14. An overhead yoke 16 which is integral with the pad box 10 sustains a toe post 18 and a heel post 20 at the lower ends 20 of which are a toe pad 22 and a plate 24 adapted respectively for engagement with the toe portion of a shoe 26 and the cone of a last 28 in the shoe. The structure described thus far is well known in the art. 25

In order to afford proper support for the projecting welt of a welt shoe or the projecting sole extension of an extension edge shoe of any type, and to apply sufficient pressure to cause the welt and sole to be securely attached to each other and 30 any tendency of the margin of the sole to roll upward to be eliminated, the welt holddown mechanism now to be described is provided.

Bracket arms 30, 32, extend upward from a plate 33 which is secured to the side of the pad box 35 10 by bolts 34 passing through slots 36 in the plate to permit the arms to be adjusted to their proper vertical positions. A hub 38 at the upper end of the bracket arm 32 is bored horizontally to permit the passage of a bolt 40, the threaded 40 end 42 of which is screwed into a collar 44, the bolt and collar being freely rotatable, about a horizontal axis, in the bore through the hub 38.

A similar hub 46 at the upper end of the bracket arm 30 is bored to receive a stud 48 which is aligned 45 with the bolt 40 and supports the forward end of a cradle member 50 which is roughly U-shaped and has its rear end portions secured to the collar 44 by bolts 52, 54 passing through holes in the ends of the cradle member and threaded into 50 the collar, as best seen in Fig. 2. Thus the cradle member 50 is suspended upon the bolt 40 and the stud 48 for a limited amount of swinging movement about a horizontal axis parallel to and above the longitudinal median line of the pad 12. 55

At its forward end the cradle member 50 is provided with a depending hub portion 56 having a vertical bore to permit the passage of a rod 58 in the lower end of which a horizontal pin 60 is secured by a set screw 62. Pivotally supported upon the pin 60 is a clevis 64 into the under side of which is screwed a vertical stud 66 constituting a hinge pin for a pair of welt supporting members 68, 70 shaped to enter and conform to the welt crease of the shoe. A compression spring 72 surrounding the rod 58 tends to force it and the welt support downward, the tension upon the spring and the limit of downward movement of the rod and welt holdown being adjustably fixed by a nut 74 threaded upon the upper end of the rod 58.

The side portions of the two welt supporting members 68 and 70 are sustained by similar arrangements of mechanism only one of which need be described in detail. A vertical rod 76, similar to the rod 58, has a horizontal threaded hole in its lower end portion to receive a screw stud 78 which passes through an upwardly extending ear 80 fastened to the welt supporting member 70. The rod 76 is surrounded by a compression spring 82 having the same function as the spring 72 which surrounds the rod 58 and a nut 83 is threaded upon the upper end of the rod 76 for the same purpose as the nut 74 upon the rod 58.

The rod 76 passes loosely through a vertical hole in a slide 84 which has a depending hub 86 to be mentioned presently. The slide 84 is guided for horizontal movement in a curved line by an arcuate slot 88 formed in a portion of the cradle member 50 and concentric with the axis of the screw stud 66 about which the welt supporting member 70 swings. When the member 70 is swung about its pivot 66 the slide 84 travels freely in the guide slot 88 and carries the supporting rod 76 with it.

In order to effect swinging movement of the member 70 about its pivot, an arm 90 is pivoted upon a stud 92 screwed into a bracket 94 which is integral with the cradle 50, the arm 90 being provided with an integral handle 96 by which it may be swung in a horizontal plane about its pivot. The rear end of the arm is forked as shown at 98 and embraces a reduced portion 100 of the hub 86 depending from the slide 84. It will be apparent that when the arm 90 is swung by means of the handle 96 the slide 84 will be moved along the slot 88 and the welt supporting member will consequently be swung about its pivot 66 into or out of engagement with the welt crease of the shoe.

In order that the other welt supporting member 68 shall swing in synchronism with the member 70, the arm 102, which moves it, is provided with a gear segment 104 which meshes with a gear segment 106 upon the arm 90, causing the two arms always to move equally and oppositely.

In the use of the apparatus just described, the holdown is opened by swinging the handle 96 in a clockwise direction, as seen when looking down upon it, and the shoe, with the sole spotted upon it, is positioned under the heel plate 24 and the toe pad 22, with the toe end of the shoe in engagement with the welt supporting members. The holdown is then closed into the welt crease of the shoe by swinging the handle 96 in a counter-clockwise direction and fluid under pressure is admitted to the pad 12 to cause the pad to apply pressure to the shoe. The strength of the springs 72, 82 is sufficient to cause the welt supporting

members to apply the proper amount of pressure to the top of the welt, but to permit the hold-down to yield upward in case the pressure should become excessive. After the attachment of the sole to the shoe is complete, the pad is deflated and the holdown opened to permit the shoe to be removed.

The bolt and slot mounting 34, 36 permits the welt supporting mechanism as a whole to be adjusted up or down until it bears the proper relation to the pad, and the nuts 74, 83 permit further vertical adjustment of the toe and side portions of the welt supporting members independently, permitting them to be swung vertically to conform to the setting of the shoe in the press. The sidewise swinging movement permitted by the mounting of the cradle 50 upon the bolt 40 and the stud 48 allows the welt support to conform to sidewise tilting or displacement of the shoe.

In the modification illustrated in Figs. 5, 6, 7 and 8 the pad box 10, pad 12, valve 14, yoke 16, toe post 18, heel post 20, and toe pad 22 are substantially the same as those already described. In this case, however, the supporting bracket which is bolted to the side of the pad box by bolts 110 has a single upwardly extending arm 112 and horizontal slots 114 permitting adjustment of the bracket lengthwise of the pad.

The upper end of the bracket arm 112 is formed to provide an elongated horizontal bearing 116 in which is slidably fitted a shaft 118 prevented from rotation in the bearing by a spline 120 which is fitted loosely enough, as shown in dotted lines in Fig. 6, to permit a small degree of oscillation of the shaft 118 about its axis. A collar 122 pinned to the shaft 118 at its outer end limits the sliding movement of the shaft toward the right as seen in Fig. 7. To the other end of the shaft 118 is pinned a hub portion 124 of a housing member 126 which carries the entire welt supporting mechanism.

The housing 126 is bored out vertically and fitted with a bushing 128 which is prevented from vertical movement by a screw 130 threaded through the wall of the housing and having its point projecting into a horizontal arcuate slot 132 cut in the wall of the bushing. The slot permits the bushing to be oscillated through a limited angle about its vertical axis while preventing vertical movement, as stated.

Fitted for vertical sliding movement in the bushing 128 is a sleeve 140 splined to the bushing by a spline 142 so that the sleeve is constrained to rotate with the bushing but can move up or down therethrough. The sleeve 140 extends upward from, and is integral with, a slide carrier 144 which has a dovetail guide in its under face containing a horizontally movable slide 146 upon which the welt support is carried.

A spindle 148, having at its lower end an enlarged head 150 upon which the slide carrier 144 is sustained, extends upward through the sleeve 140 and has pinned to its upper end a collar 152 provided with a laterally extending pin 154 surrounded by the rotatable shank 156 of a T-handle 158 which is retained upon the pin by a screw 160 whose point engages in a groove at 162 near the outer end of the pin. The shank 156 carries a cam 164 arranged to engage a vertically stationary shelf 166 upon the housing 126 when the handle 158 is turned about its horizontal axis. By thus turning the handle, causing the cam to engage the top of the shelf, the collar 152, the spindle 148 which is pinned to it, and the slide carrier 144 sustained by the

spindle are raised or lowered as the case may be. By swinging the handle in a horizontal plane the whole assembly is swung in one direction or the other about the vertical axis of the spindle 148 between limits determined by two ears 168 projecting radially from the collar 152 and engageable alternatively with a stationary stop pin 170 screwed into the housing 126.

- An upright pin 172 screwed into the top of the slide 146 engages in a radial notch in the head 150 and serves to move the slide longitudinally in the slide carrier 144 when the spindle 148 is turned by swinging the handle 158 to the right or left. A horizontal trunnion 174 is carried by the slide 146 and has a laterally projecting pin 176 upon which pressure is exerted by a compression spring 178 tending to move the trunnion rearward in the slide 146, toward the shoe.
- Secured to the under side of the trunnion 174 by bolts 180 and 181 is a cross plate 182 in which are secured two vertical studs 184 constituting pivots for a pair of actuating arms 186 which serve to open and close the welt holddown relatively to the shoe.

The bolt 180 is extended downwardly as shown at 188 to constitute a pivotal mounting for the two welt supporting sections 190, 192. Pins 194 extending upward from the sections of the welt support engage in slots 196 formed in the ends of the arms 186, causing the holddown to be opened or closed when the arms are swung about their pivots 184.

Fixed to each long arm 186 is a short arm 198 against which bears a compression spring 200, the force of which tends to swing the arms 186 outward. Disposed between the ends of the two short arms 198 is a wedge shaped member 202 which is secured to the slide 146 and moves therewith. When the slide is moved from its extreme left hand position, as viewed in Fig. 6, toward the right by turning the spindle 148, the welt support is first carried lengthwise into contact with the toe of the shoe, whereupon it and the trunnion 174 which sustains it stop. Yielding of the spring 178 permits continued movement of the slide 146, forcing the double wedge 202 against the inner faces of the short arms 198 and swinging the long arms 186 inward to close the holddown members into the welt crease of the shoe. Rocking movement of the trunnions 174 permits transverse rocking of the holddown to accommodate itself to transverse tilting of the shoe, twisting of the handle 158 about its horizontal axis raises or lowers the holddown to adjust its height to the vertical position of the welt crease of the shoe, looseness in the fitting of the spline 120 permits the holddown to swing about the horizontal transverse axis of the shaft 118 to adjust itself for vertical longitudinal tilting of the shoe, and the whole mechanism may be slid bodily horizontally in the direction of the axis of the shaft 118 to accommodate it to the transverse position of the shoe upon the pad. All of these movements are accomplished either automatically or by manipulation of the single handle 158.

The sections 192 of the welt supporting element are inclined on the outside as shown at 204, Fig. 7, and when the pad 12 is inflated it will bulge up around the outside of the welt support, as at 206, holding the welt supporting elements 192 tightly in the welt crease of the shoe and, indeed, tending to force them inward even more tightly than they have been forced

by swinging the handle 158. The result of this is that the welt support is very firmly held in its operative position as soon as the pad is fully inflated, and the more highly the pad is inflated the more firmly the welt support is held, so that there is no necessity for holding it in manually after inflation of the pad.

Mounted upon the heel post 20 is a plate 208, the lower face of which is corrugated as shown at 210. Slidably mounted upon bolts 212 passing through slots 214 in its upper portion is a last plate 216, the upper face of which is corrugated similarly to the face 210 of the plate 208. The last plate slots 214 are loose enough on the bolts 212 to permit a slight vertical movement of the plate, which carries a short pin 218 adapted to enter the usual pin hole 220 in the heel portion of the last 28. As soon as pressure is applied by inflation of the pad 12, the last plate 216 is automatically locked to the plate 208 by engagement of the corrugated surfaces of the two plates and the shoe is firmly held against longitudinal displacement by the thrust of the holddown against the toe end of the shoe. In the ordinary use of the apparatus the last shoe may be positioned upon the pad, with the pin 218 in the pin hole 220 in the last, and the pad partially inflated, sufficiently to cause the plate 216 to be locked to the plate 208, before the handle 158 is swung to force the holddown 30 against the toe of the shoe and then to close it into the welt crease. After the holddown has been accurately positioned and forced into the welt crease the inflation of the pad will be completed, whereupon, as stated above, the handle 35 need no longer be held.

Having described the invention, what is claimed as new and desired to be secured by Letters Patent is:

1. In a sole attaching apparatus, a pad support, a pad upon the support, a yoke sustained by the pad support, heel and toe supports sustained by the yoke, and a welt holddown sustained by the pad support independently of the yoke and of the heel and toe supports.

2. In a sole attaching apparatus, a pressure pad, and a welt holddown sustained above the pad for transverse swinging movement about an axis extending longitudinally of a shoe upon the pad and disposed substantially above the sole of the shoe.

3. In a sole attaching apparatus, an expandable and contractible welt holddown supported for swinging movement about an overhead horizontal axis and a single handle member constructed and arranged both to effect said swinging movement and to expand and contract the holddown about a shoe.

4. In a sole attaching apparatus, a pressure pad adapted to support a shoe, and a welt holddown sustained above the pad, said welt holddown being supported for free swinging movement, within limits, about separate horizontal axes extending transversely and longitudinally of the shoe.

5. In a sole attaching apparatus, a pressure pad adapted to support a shoe, and a welt holddown sustained above the pad, said welt holddown being supported for swinging movement about three separate axes extending, respectively, transversely, longitudinally and vertically of the shoe.

6. In a sole attaching apparatus, welt holddown means comprising a welt supporting member mounted for swinging movement about an upright axis and for vertical movement in the direction of said axis, and a single handle for ef- 75

- fecting both of said movements, each independently of the other.
7. In a sole attaching apparatus, a carrier, a welt holdown sustained by the carrier, a vertically movable spindle upon which the carrier is supported, a handle rotatably secured to the spindle, a cam fixed to the handle, and a stationary shelf arranged to be engaged by the cam, whereby rotation of the cam by turning the handle will raise or lower the spindle and the holdown.
8. In a sole attaching apparatus, a pressure pad adapted to support a shoe, and a welt holdown sustained above the pad, said welt holdown being supported for swinging movement about three separate axes extending, respectively, transversely, longitudinally and vertically of the shoe, and for sliding movement transversely, longitudinally and vertically of the shoe.
9. In a sole attaching apparatus, welt holdown means comprising a contractile welt holdown mounted upon a support which is slidable longitudinally of the holdown, a slide in which said support is guided, and means carried by the slide for contracting the holdown when the slide is moved longitudinally relatively to the support.
10. In a sole attaching apparatus, a pressure pad adapted to support a shoe, a contractile welt holdown sustained above the pad and movable longitudinally thereof, and means for automatically contracting the holdown about a shoe upon the pad when it is forced against the toe end of the shoe.
11. In a sole attaching apparatus, a pressure pad, a contractile welt holdown sustained above the pad, and a movable wedge cooperating with the holdown to contract the latter when the wedge is moved.
12. In a sole attaching apparatus, welt holdown means comprising a contractile welt sup-
- port mounted for vertical sliding movement, a handle mounted for both swinging and twisting movement, and connecting means for contracting the welt support when the handle is swung and raising or lowering the welt support when the handle is twisted.
13. In a sole attaching apparatus, an inflatable pressure pad adapted to support a lasted shoe, a welt holdown sustained above the pad and movable longitudinally thereof into engagement with the shoe, a last engaging member sustained above the pad and movable longitudinally thereof, and means for locking the last engaging member against longitudinal movement when pressure is applied to the shoe by inflation of the pad, whereby the shoe is held against displacement by the thrust of the holdown.
14. In a sole attaching apparatus, a pressure pad, a cradle sustained above the pad for transverse swinging movement about an axis extending longitudinally of a shoe upon the pad and disposed substantially above the sole of the shoe, and a welt holdown suspended from the cradle.
15. In a sole attaching apparatus, a pressure pad, a cradle sustained upon coaxial pivots above the pad, the axis of the pivots being disposed longitudinally of, and spaced a considerable distance above, the pad, a welt holdown suspended from the cradle, and springs interposed between the holdown and the cradle to permit the holdown to yield upward toward the cradle.
16. In a sole attaching apparatus, a pressure pad, a cradle sustained above the pad for limited longitudinal swinging movement about an axis spaced a considerable distance above the pad and extending transversely thereof, a welt holdown suspended from the cradle and positioned near the pad, and springs interposed between the holdown and the cradle to permit the holdown to yield upward toward the cradle.

JOHN T. LANCASTER.
